Arthur B. Jenkins,
ATTORNEY

UNITED STATES PATENT OFFICE.

ROBERT J. WATTS, OF BENTON HARBOR, MICHIGAN.

DOFFER FOR IRONING MACHINES.

Application filed October 27, 1926. Serial No. 144,458.

My invention relates to the class of machines employed for ironing fabrics, and an object of my invention, among others, is the production of a machine of this kind that shall have simple and effective means for removing articles being ironed from the cylinder or drum upon which the ironing takes place.

One form of machine embodying my invention and in the construction and use of which the objects herein set out, as well as others, may be attained, is illustrated in the accompanying drawings, in which—

Figure 1 is a view of a fragment of an ironing machine, illustrating my improved doffer applied thereto.

Figure 2 is a top view of that part of the machine illustrated in Figure 1.

Figure 3 is a top view of a portion of the doffer mechanism.

Figure 4 is a view in section on a plane denoted by the dotted line 4—4 of Figure 3.

In the accompanying drawings the numeral 5 indicates a portion of the end of the frame of an ironing machine to which my improved doffing attachment is affixed and 6 indicates the cylinder in contact with which the articles to be ironed are passed, this cylinder being heated in a manner common to machines of this class. The cylinder rotates in the direction indicated by the arrow in Figure 1, and the articles are carried between said drum and an endless apron 7 passing at one end around a roll 8 and being supported at various points throughout its length by other rolls or similar devices positioned to maintain the apron in contact with the drum throughout a considerable portion of the circumference of the latter, and in a manner common to machines of this class. At a point adjacent to the roll 8 where the apron 7 leaves the drum, and between such roll and the point where the articles being ironed pass in between the drum and apron 7 my improved doffing attachment is located.

This attachment comprises a bar 9 extending across the machine between the two ends thereof and secured to its upper edges, this bar supporting the several members of the attachment, all of which are of the same construction and for which reason the description herein will be confined to a single member. Such member is composed of a base plate 10 having a dove-tail shaped projec-

tion 11 fitted in a dove-tail shaped groove 12 extending lengthwise of the bar 9, and said member also includes a knuckle 13 that serves as a pivotal support for the rest of the attachment. This embodies a knife support 14 having ears 15 to receive a pintle extending through said ears and the knuckle 13. An opening 16 is made in the support and the shank 17 of a doffing knife 18 extends into said hole.

Said shank extends from the back edge of the knife at substantially its lengthwise center and through a hole extending from the edge of the support 14 into the opening 16 and is pivotally mounted therein.

A series of tapes 19 pass through cut away portions 20 in the adjacent edges of the supports 14, said tapes passing about the edges of the notches 20 and about tape supporting rolls 21 rotatably mounted in roll supports 22 secured to and rising from the ends 5.

The knife supports are of such weight as to maintain the knives 18 in contact with the cylinder 6 by the action of gravity, and these supports are so located with respect to the cylinder 6 and roll 8 that an upward pull is exerted by the tapes 19, and this pull on the knife counteracts the action of gravity merely to such extent as to maintain a sufficient pressure of the knives 18 against the cylinder to effect the desired results. The knives 18 are freely movable on their pivots to readily accommodate themselves to any irregularity in the drum or cylinder, and the knife supports 14 are also freely movable to accommodate themselves to varying conditions in the operation of the machine, thus providing for efficiency. The structures are such as to enable them to be readily and comparatively inexpensively made and also to be readily attached to or removed from the machine.

In accordance with the provisions of the patent statutes I have described the principles of operation of my invention, together with the device which I now consider to represent the best embodiment thereof; but I desire to have it understood that the device shown is only illustrative and that the invention may be carried out by other means and applied to uses other than those above set out.

I claim—

1. A doffer including a pivotally mounted

knife support, with a hole extending inward from the edge thereof, and a doffing knife located at the edge of said support and having a shank extending into said hole and freely pivotally movable therein.

2. A doffer including a pivotally mounted knife support having an opening therethrough and a hole extending from its edge into said opening, and a doffing knife located 10 at the edge of said support and having a shank projecting through said hole into said opening, and freely pivotally movable therein.

3. A doffer including a base plate, a dove-tail shaped projection thereon to fit a groove of similar shape in a doffer support, a doffing knife support pivotally attached to

said plate, a doffing knife pivotally attached to said support.

4. An ironing machine including a frame, 20 a supporting bar secured to said frame and having a lengthwise groove, a series of doffing knife supports rigidly but removably secured in said groove, and doffing knives freely pivotally attached to said supports. 25

5. An ironing machine including a frame, a supporting bar secured to said frame and having a dove-tail shaped groove extending lengthwise therein, a series of doffing knife supports having projections removably fitting said grooves, and a doffing knife pivotally sustained by each of said supports. 30

ROBERT J. WATTS.
